UNITED STATES PATENT OFFICE.

WILLIAM J. POPE AND JULIUS HÜBNER, OF MANCHESTER, ENGLAND.

DESIGN FOR FABRIC.

No. 37,524.

Specification for Design.

Patented Aug. 29, 1905.

Application filed June 13, 1904. Serial No. 212,439. Term of patent 14 years.

To all whom it may concern:

Be it known that we, WILLIAM JACKSON POPE and JULIUS HÜBNER, British subjects, residents of Manchester, in the county of Lancaster, England, have invented a new, original, and ornamental Design for Fabric, of which the following is a specification, reference being had to the accompanying drawing, forming a part thereof.

The figure is a plan view, on a very greatly

enlarged scale, of a piece of fabric showing our design, the actual design being of substantially microscopic proportions.

What we claim is—

The ornamental design for fabric, as shown.

W. J. POPE.

JUL. HÜBNER.
